COMBINED NEWSPAPER AND MAIL BOX

Leo C. Letzkus, 436 Parker Drive, Pittsburgh, Pa.

Filed Dec. 31, 1959, Ser. No. 58,888

Term of patent 14 years

(Cl. D74—9)

FIG. 1.

FIG. 2.

FIGURE 1 is an isometric view of the front of a combined newspaper and mail box, showing my new design;

FIGURE 2 is an isometric view of the rear thereof; and

FIGURE 3 is a side elevational view thereof, as it appears with one of the lids in raised position.

My design is characterized by a rectangularly shaped combined newspaper and mail box having superimposed on the front face of the newspaper box a like rectangularly shaped mail box of considerably smaller size centrally positioned thereon. The end plates for the slanted covers are curved at the rear portion thereof and overlap the sides, all as shown.

I claim:

The ornamental design for a combined newspaper and mail box, as shown and described.
